(57) **CLAIM**

The ornamental design for a confection, as shown and described.

DESCRIPTION

FIG. 1 is a perspective view of a first embodiment of a confection showing my new design;

FIG. 2 is a front view of the design shown in FIG. 1;

FIG. 3 is a rear view of the design shown in FIG. 1;

FIG. 4 is a left side view of the design shown in FIG. 1;

FIG. 5 is a right side view of the design shown in FIG. 1;

FIG. 6 is a top view of the design shown in FIG. 1;

FIG. 7 is a bottom view of the design shown in FIG. 1;

FIG. 8 is another perspective view of the first embodiment of a confection showing my new design with alternate unclaimed subject matter;

FIG. 9 is a front view of the design shown in FIG. 8;

FIG. 10 is a rear view of the design shown in FIG. 8;

FIG. 11 is a left side view of the design shown in FIG. 8;

FIG. 12 is a right side view of the design shown in FIG. 8;

FIG. 13 is a top view of the design shown in FIG. 8;

FIG. 14 is a bottom view of the design shown in FIG. 8;

FIG. 15 is a perspective view of a second embodiment of a confection showing my new design;

FIG. 16 is a front view of the design shown in FIG. 15;

FIG. 17 is a rear view of the design shown in FIG. 15;

FIG. 18 is a left side view of the design shown in FIG. 15;

FIG. 19 is a right side view of the design shown in FIG. 15;

FIG. 20 is a top view of the design shown in FIG. 15;

FIG. 21 is a bottom view of the design shown in FIG. 8;

FIG. 22 is a perspective view of a third embodiment of a confection showing my new design;

FIG. 23 is a front view of the design shown in FIG. 22;

FIG. 24 is a rear view of the design shown in FIG. 22;

FIG. 25 is a left side view of the design shown in FIG. 22;

FIG. 26 is a right side view of the design shown in FIG. 22;

FIG. 27 is a top view of the design shown in FIG. 22; and,

FIG. 28 is a bottom view of the design shown in FIG. 22.

The broken lines shown in the drawings represent unclaimed portions of the confection and form no part of the claimed design.

1 Claim, 28 Drawing Sheets
